DESIGN FOR A SHOE

Harry Sobel, Los Angeles, Calif.

Application November 25, 1941, Serial No. 104,324

Term of patent 3½ years

To all whom it may concern:

Be it known that I, Harry Sobel, a citizen of the United States of America, residing in Los Angeles, county of Los Angeles, and State of California, have invented a new, original, and ornamental Design for a Shoe, of which the following is a specification, reference being had to the accompanying drawing, forming part thereof.

The figure on the drawing is a front perspective view of a shoe showing my new design. The opposite side presenting substantially the same appearance as the side shown.

I claim:

The ornamental design for a shoe, substantially as shown and described.

HARRY SOBEL.
